THREAD CONTROL FOR PNEUMATIC
THREAD EXTRACTORS

Clifford Darwin, Worcester, Mass., assignor to
Crompton & Knowles Loom Works, Worcester,
Mass., a corporation of Massachusetts

Application June 9, 1939, Serial No. 278,306

10 Claims. (Cl. 139—256)

This invention relates to improvements in thread removers for weft replenishing looms and it is the general object of the invention to provide means for confining resilient weft threads 5 to positions where they can respond to the action of the thread remover.

There has recently come into use a form of thread remover or extractor for weft replenishing looms embodying a pneumatic tube having 10 an intake mouth into which air was caused to rush by means of an air pump or the like. The intake mouth is so placed at the time of transfer as to be in the path of the thread extending from the selvage into the shuttle box as the lay 15 moves rearwardly. In order to direct the thread toward the mouth it is customary to use a tongue projecting downwardly and forwardly in cooperation with a mass of deformable material such as pile fabric across which the thread lies. The 20 deformable material has a frictional contact with the thread sufficient to cause the latter to move rearwardly toward the intake mouths.

In order that the thread may be free to respond to the thread remover the thread is cut at a point 25 near the shuttle eye on a transferring beat of the loom while the lay is in a forward part of its reciprocating motion, and provision is made to lower the thread remover from its normally raised position by movement of the transerrer means. 30 As a result, the thread remover is in its downward position when the thread is cut at the shuttle eye.

When the weft being woven is resilient, as in those types of threads used for the weaving of 35 crepe, it has a tendency because of its elasticity to snap back toward the selvage. It is an important object of my present invention to provide means which will extend into the path of the thread as the latter moves toward the selvage, 40 thereby resisting its motion toward the cloth and preventing it from moving to such a position as would prevent cooperation with the thread remover. This result I may accomplish by placing a plate on the tube and extending it forwardly 45 from the intake mouth over the deformable material.

In order that the thread may not snap forwardly out of the range of the thread remover I form the thread guard so that the front end 50 thereof projects below the top of the deformable material or into the piles of the friction fabric extending across the top of the lay and at the same time may keep the rear part of the guard spaced slightly above the friction material at a 55 point adjacent to the intake mouth. In this way

the thread is limited in its forward motion away from the intake mouth, and is likewise prevented from moving upwardly out of the range of the extractor. I have found that after cutting a portion of the thread will either curl on itself or 5 present a curved shoulder to the guard and the latter dampens the thread movement and causes it to lie across the friction material in a position where it can respond to the draft of air moving into the intake mouth.

With these and other objects in view which will appear as the description proceeds, my invention resides in the combination and arrangement of parts hereinafter described and set forth in the 10 claims.

In the accompanying drawing, wherein there are two forms of my invention set forth,

Fig. 1 is a side elevation of parts of a weft replenishing mechanism seen from the center of the loom with the preferred form of my invention 20 applied thereto, parts in section,

Fig. 2 is a plan view of the lay taken in the direction of arrow 2, Fig. 1, with parts in section,

Fig. 3 is a vertical section on line 3—3, Fig. 2, showing the preferred form of the invention, 25

Fig. 4 is a detail front elevation taken in the direction of arrow 4, Fig. 2, and

Fig. 5 is similar to Fig. 3 but showing a modified form of the invention.

Referring to the drawings, I have shown a loom 30 frame 15, breast beam 16 and lay 17 of usual construction except for matter to be described hereinafter. The lay has a shuttle box R to receive a shuttle S from which a weft thread W extends toward the adjacent selvage of the fabric F. 35

The reciprocating bobbin magazine 30 may oscillate about an axis 31 by mechanism shown for instance in prior Patent No. 2,128,974. The magazine includes a transerrer arm 35 movable about a pivot 36 when a latch 37 is struck in the 40 usual manner by forward motion of a dagger 38 on the lay, thus depressing the transerrer arm to effect transfer. A cutter arm 40 pivoted about a vertical pin 41 carries a cutter blade 44 to co-operate with a plate 45 on the shuttle to sever 45 the weft W on transferring beats of the loom at a point near the shuttle eye.

A rod 70 mounted on a carrier 71 pivoted on a fixed stud 72 carries a vertical tube 90 connected by a hose 91 to an air pump not shown herein 50 but similar to that set forth in co-pending application Serial No. 190,637. The tube 90 is held in a head 82 on the forward end of rod 70 by a set screw 101, and a roll 83 on the head 82 is placed for engagement with a cam 84 secured to 55

the transferrer arm 35. A friction disk 75 between disks 73 and 74, Fig. 1, holds the tube 90 and rod 70 against pivotal motion around stud 72 by their own weight and these parts must therefore be acted upon positively in order to effect their movement. A resetting screw 69 on the lay is positioned for engagement with the carrier 71 as the lay approaches back center, while cooperation between the cam 84 and the roll 10 83 operates to lower the tube 90 when the trans- ferrer arm descends as the lay approaches its front center position on transferring beats of the loom.

The lay is provided on its upper surface with 15 a transverse slot 66 in which is mounted a mass of deformable material such as pile tufts 61. A tongue 92 extends diagonally downwardly and forwardly from the bottom of the tube and moves relatively to the pile tufts in a forward 20 direction at a level below the weft thread which floats on the top of the pile tufts as the lay re- cedes. The bottom of the tube 90 is provided with an intake mouth 93 into which air is drawn for the purpose of attracting the thread. The 25 inrush of air generally occurs during the back- ward stroke of the lay which also moves the thread in frictional contact with the pile tufts toward the intake mouth 93.

The matter thus far described operates sub- 30 stantially the same as that set forth in co-pending application Serial No. 190,637 to which refer- ence may be had for a more complete description of the structure and operation of the previously 35 described parts which effect lowering and subsequent raising of the tube 90 and also the general function of the pile tufts 61. It is thought suffi- cient for present purposes to state that the tube 90 is normally raised and is depressed on a trans- ferring beat of the loom when the lay is at or 40 near its front center position to lower the bottom end of tube 90 toward the pile tufts 61.

As already stated my present invention re- lates to guard means to confine the thread to the 45 zone of influence of the thread remover. It is to be understood that if the weft W is resilient it will tend to snap toward the selvage of the fabric F when severed at the shuttle eye as already de- scribed. The thread is sufficiently active to move 50 itself off the pile tufts and out of the range of influence of the thread remover unless some pro- vision is made to insure its frictional contact with the pile tufts so that the latter can move the thread toward the intake mouth.

In carrying the preferred form of the present 55 invention into effect I secure a vertical plate or web 59 to the bottom of the tube 90 and from the lower edge thereof in such a way that when the tube 90 is down on a transferring beat that part of the lower edge indicated at 51 in front of and 60 adjacent to the intake mouth 93 is slightly above the tops of the pile tufts 61, while the forward part of the lower edge indicated at 52 is low enough to extend into the deformable material below the tops of the pile tufts. By this construc- 65 tion I provide a thread trap the top of which is defined by the surface 51, the forward end of which is determined by the point at which the guard enters the pile fabric, the lower part of which is defined by the tops of the tufts 61, and 70 the rear part of which is defined by the tube and parts carried thereby. The thread is therefore effectively restrained as to objectionable lateral or vertical motion.

In the modification set forth in Fig. 5, sub- 75 stantially the whole of the bottom edge 55 of

plate 54 extends below the tops of the pile tufts. This edge 55, it will be noted, is above the bottom of the tongue 92, and this relation is also true for the front part of plate 50 in the preferred form.

In operation, the thread will extend from the selvage across the pile fabric and into the shuttle box as indicated in Fig. 2 immediately before a transferring operation of the loom. When the transferrer arm descends it moves the tube down 10 so that the guard will occupy a position over the thread as indicated in Fig. 3. In the preferred form the thread will ordinarily lie under the bottom edge 51 and be trapped between said edge 15 and the pile tufts. When the lay reaches front center the thread cutter will sever the thread and the free end of the latter will immediately snap toward the selvage because of its inherent resilience. In the preferred form the thread trap is so narrow that the thread will have difficulty 20 in moving through it without engagement with the plate 50 and the latter will therefore obstruct movement of the thread toward the selvage. The edge 51 will be low enough to prevent substantial upward motion of the thread away from the 25 pile tufts and the latter will ordinarily have sufficient contact with the thread to move the latter toward the intake mouth and the tongue during the succeeding backward motion of the 30 lay.

In the modified form of the invention the bot- 35 tom of the plate 54 will press the thread into the pile tufts a short distance sufficient to form a slight bight in the thread. This bight or crimp operates effectively to prevent motion of the 40 thread away from the pile tufts, without interfer- ing with the tractive force exerted pneumati- cally on the thread.

In both forms of the invention I find that the 45 thread is restricted in its upward motion away from the pile tufts and in its relative forward motion away from the intake mouth, and that in both forms the guard plates snub or check motion of the free end of the thread toward the 50 selvage.

It is to be understood that the forward motion 55 of the lay and the descent of tube 90 are coordi- nated in such a way as to cause the guard to move down on the thread after the latter has been moved forwardly by advance motion of the lay 60 to a position under the guard. As already de- scribed, the tube 90 will be raised on the following back center position of the lay and therefore have no contact with the threads extending from the selvage into the shuttle box on non-trans- ferring beats of the loom. The sweep of the lay 65 is such that it will reach a position sufficiently behind the tube 90 at the time of picking to allow the shuttle to pass behind the tube without con- flict therewith.

In the foregoing description I have stated that the thread has a tendency because of its inherent resilience to move toward the selvage at the time of cutting. If the thread is not pinched between the shuttle and the binder this tendency asserts 70 itself immediately after cutting and the thread will snap toward the selvage while the lay is on front center position. If, on the other hand, the thread is pinched between the shuttle and the binder it is not released until the time of picking, at which time the tendency of the thread to recoil on itself and move toward the selvage is asserted. Under the latter conditions the thread will nor- mally be nearer the intake mouth than is the case when the thread is released while the lay 75

is on front center, but I have found that a resilient thread which is not released until the time of picking will nevertheless be active enough to tend to spring to a position out of the range of the 5 thread remover. My invention is therefore effective whether the thread is released either at transfer or picking.

From the foregoing it will be seen that I have provided a thread control for a pneumatic thread 10 remover or extractor which acts to nullify the tendency of the thread to move out of the range of the thread remover because of its inherent resilience. It will further be seen that the thread guard not only resists longitudinal motion of the 15 thread toward the selvage but also limits upward motion of the thread and furthermore cooperates with the pile tufts to limit forward motion away from the intake mouth. It will further be seen that my invention will operate either 20 with a narrow thread trap immediately above the pile tufts as shown in the preferred form of the invention or by means of the modified plate 54 which sinks the thread a short distance below the tops of the pile tufts.

Having thus described my invention it will be seen that changes and modifications may be made therein by those skilled in the art without departing from the spirit and scope of the invention 30 and I do not wish to be limited to the details herein disclosed, but what I claim is:

1. In a thread control mechanism for a loom having a lay provided with a shuttle from which a thread extends to the adjacent selvage, a mass 35 of deformable material extending across the top of the lay under the thread, means to cut the thread at a point beyond the deformable material with respect to the selvage, a pneumatic thread extractor having a tongue extending below the top of the deformable material and having an 40 intake mouth, the deformable material moving the thread by frictional contact therewith toward the intake mouth as the lay moves rearwardly, and means extending forwardly from the thread extractor over the thread to prevent the latter 45 after cutting from moving upwardly away from the deformable material.

2. In a thread control mechanism for a loom having a lay provided with a shuttle from which a thread extends to the adjacent selvage, a mass 50 of deformable material extending across the top of the lay under the thread, means to cut the thread at a point beyond the deformable material with respect to the selvage, a pneumatic thread extractor having a tongue extending below the 55 top of the deformable material and having an intake mouth, the deformable material moving the thread by frictional contact therewith toward the intake mouth as the lay moves rearwardly, and means extending over the thread and below the 60 top of the deformable material at a point spaced from and in front of the tongue to prevent the thread after cutting from moving upwardly away from the deformable material.

3. In a thread control mechanism for a loom 65 having a lay provided with a shuttle from which a thread extends to the adjacent selvage, a mass of deformable material extending across the top of the lay under the thread, means to cut the thread at a point beyond the deformable material 70 with respect to the selvage, a pneumatic thread extractor having a tongue extending below the top of the deformable material and having an intake mouth, the deformable material moving the thread by frictional contact therewith toward the intake mouth as the lay moves rearwardly, and a 75

thread guard extending over the deformable material forwardly from the intake mouth to prevent the thread after cutting from moving upwardly away from the deformable material.

4. In a thread control mechanism for a loom 5 having a lay provided with a shuttle from which a thread extends to the adjacent selvage, a mass 10 of deformable material extending across the top of the lay under the thread, means to cut the thread at a point beyond the deformable material with respect to the selvage, a pneumatic thread extractor having a tongue extending below the top of the deformable material and having an intake mouth, the deformable material moving the 15 thread by frictional contact therewith toward the intake mouth as the lay moves rearwardly, and a thread guard extending into the deformable material at a point in front of the intake mouth, said guard having a portion between said point and the intake mouth above the deformable material, 20 the guard preventing motion of the thread forwardly with respect to the deformable material to a position in front of the guard and also preventing motion upwardly away from said deformable material. 25

5. In a thread control mechanism for a loom having a lay provided with a shuttle from which a thread extends to the adjacent selvage, a mass 30 of deformable material extending across the top of the lay under the thread, means to cut the thread 35 at a point beyond the deformable material with respect to the selvage, a pneumatic thread extractor having a tongue extending below the top of the deformable material and having an intake mouth, the deformable material moving the 40 thread by frictional contact therewith toward the intake mouth as the lay moves rearwardly, and a thread guard having a portion adjacent to the thread extractor above and out of contact with the deformable material and having another portion spaced forwardly from the intake mouth and extending below the top of the deformable material, said guard preventing substantial upward displacement of the thread away from the 45 deformable material.

6. In a thread control mechanism for a loom having a lay provided with a shuttle from which a thread extends to the adjacent selvage, a mass 50 of deformable material extending across the top of the lay under the thread, means to cut the thread at a point beyond the deformable material with respect to the selvage, a pneumatic thread extractor having a tongue extending below the top of the deformable material and having an intake mouth, the deformable material moving 55 the thread by frictional contact therewith toward the intake mouth as the lay moves rearwardly, and means projecting forwardly from the thread extractor and extending below the top of the deformable material to form with the latter a trap 60 for the thread in front of the intake mouth.

7. In a thread control mechanism for a loom having a lay provided with a shuttle from which a thread extends to the adjacent selvage, a mass 65 of deformable material extending across the top of the lay under the thread, means to cut the thread at a point beyond the deformable material with respect to the selvage, a pneumatic thread extractor having a tongue extending below the top of the deformable material and having an intake mouth, the deformable material moving the thread by frictional contact therewith toward the intake mouth as the lay moves rearwardly, and a vertical plate projecting forwardly from the 70 thread extractor above the deformable material 75

and projecting below the latter at a point spaced from and in front of the intake mouth to prevent the thread after cutting from moving upwardly from said deformable material.

5. 8. In a thread control mechanism for a loom having a lay provided with a shuttle from which a thread extends to the adjacent selvage, a mass of deformable material extending across the top of the lay under the thread, means to cut the 10 thread at a point beyond the deformable material with respect to the selvage, a pneumatic thread extractor having a tongue extending below the top of the deformable material and having an intake mouth, the deformable material 15 moving the thread by frictional contact therewith toward the intake mouth as the lay moves rearwardly, and a thread guard above the deformable material extending transversely of the thread to engage and resist motion of a resilient 20 weft thread tending to move toward the selvage after cutting.

9. In a thread control mechanism for a loom having a lay provided with a shuttle from which a thread extends to the adjacent selvage, a mass 25 of deformable material extending across the top of the lay under the thread, means to cut the thread at a point beyond the deformable material with respect to the selvage, a pneumatic thread extractor having a tongue extending below the top of the deformable material and having an 30 intake mouth the deformable material moving the thread by frictional contact therewith toward the intake mouth as the lay moves rearwardly, the thread being resilient and tending to move toward the selvage after being cut, and a 35

guard extending above but close to the deformable material and forwardly from the intake mouth to resist said motion of the thread toward the selvage by engagement of the thread with the guard.

10. In a thread control mechanism for a loom having a lay provided with a shuttle from which a thread extends to the adjacent selvage, a mass of deformable material extending across the top of the lay under the thread, means to cut the 10 thread at a point beyond the deformable material with respect to the selvage, a pneumatic thread extractor having a tongue extending below the top of the deformable material and having an intake mouth, the deformable material moving 15 the thread by frictional contact therewith toward the intake mouth as the lay moves rearwardly, the thread being resilient and tending to move toward the selvage after being cut, and a guard extending forwardly from the intake 20 mouth and having a portion above the deformable material adjacent to the mouth and having another portion projecting below the top of the deformable material at a point spaced forwardly from the mouth, said guard including a vertical 25 plate extending transversely of the thread, said guard and deformable material forming a trap to prevent movement of the thread upwardly from the deformable material and limit forward movement of the thread away from the mouth, and the vertical plate tending to resist motion of a resilient 30 thread to move toward the selvage after cutting.

CLIFFORD DARWIN. 35
